US00D888673S

(12) **United States Design Patent** (10) **Patent No.:** **US D888,673 S**
Furutani (45) **Date of Patent:** **** Jun. 30, 2020**

(54) **SEMICONDUCTOR MODULE**(71) Applicant: **ROHM CO., LTD.**, Kyoto-shi, Kyoto (JP)(72) Inventor: **Ryuichi Furutani**, Kyoto (JP)(73) Assignee: **ROHM CO., LTD.**, Kyoto (JP)(**) Term: **15 Years**(21) Appl. No.: **29/673,185**(22) Filed: **Dec. 12, 2018**(30) **Foreign Application Priority Data**Jun. 26, 2018 (JP) 2018-014082
Jun. 26, 2018 (JP) ..... 2018-014084(51) **LOC (12) Cl.** ..... **13-03**(52) **U.S. Cl.**USPC ..... **D13/182**(58) **Field of Classification Search**USPC D13/182; 257/678, 684, 690, 691;

Primary Examiner — Elizabeth J Oswecki(74) *Attorney, Agent, or Firm* — Hamre, Schumann,
Mueller & Larson, P.C.(57) **CLAIM**The ornamental design for a semiconductor module, as
shown and described.**DESCRIPTION**FIG. 1 is a front, top and right side perspective view of a first embodiment of a semiconductor module showing my new
design;FIG. 2 is a rear, bottom, and left side perspective view
thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, the left side view being
a mirror image of FIG. 7; and,FIG. 8 is a cross sectional view taken along line 8-8 in FIG.
5.**1 Claim, 6 Drawing Sheets**(56)
